(57) **CLAIM**

I claim the ornamental design for a wine bottle that transforms into a wine glass, as shown and described.

DESCRIPTION

FIG. 1 is a top perspective view of a wine bottle that transforms into a wine glass, in bottle form, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top perspective view of a wine bottle that transforms into a wine glass, in wine glass form, showing my new design;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof; and,

FIG. 14 is a bottom plan view thereof.
